UNITED STATES PATENT OFFICE.

EDWARD PERRIN, OF KIDDERMINSTER, ENGLAND, ASSIGNOR TO JOSEPH WILD & CO., OF NEW YORK CITY.

DESIGN FOR A CARPET-PATTERN.

Specification forming part of Design No. 5,446, dated December 19, 1871.

To all whom it may concern:

Be it known that I, EDWARD PERRIN, of Kidderminster, in the county of Worcester, England, have invented a new and original Design for a Carpet, of which the following is a specification:

In the drawing, *e e* represent two longitudinal side figures, and *f* a longitudinal middle figure, arranged in parallel rows.

The nature of my design is fully represented in

the accompanying photographic illustration, to which reference is made.

I claim as my invention—

The design for a carpet, as shown.

Witnesses: EDW. PERRIN.
